UNITED STATES PATENT OFFICE

CHARLES E. MORRIS, OF LEAVENWORTH, KANSAS

CENTER POLE AND SUPPORT THEREFOR

Application filed July 26, 1926. Serial No. 124,937.

My invention relates to improvements in center poles and supports therefor. It relates particularly to center pole structures adapted for use with carousels, and which are adapted to be disassembled and moved from place to place.

One of the objects of my invention is to provide a novel center pole and support therefor, which can easily and quickly be set up or taken down, which is held together simply by the interlocking of the parts thereof, which eliminates screws and bolts, which is strong, durable, not liable to get out of order, and which is simple and is cheap to manufacture.

A further object of my invention is the provision of a novel means for releasably locking together the different parts of the structure.

Another object of my invention is to provide a novel means for integrally fastening a ring on a bar without having the welding or other fastening material used get upon the exterior of the ring so as to destroy the regular contour of the periphery of the ring.

My invention provides further novel means for releasably interlocking the pole to beams which support it.

The novel features of my invention are hereinafter fully described and claimed.

In the accompanying drawings, which illustrate the preferred embodiment of my invention,

Fig. 1 is a side elevation of my improved center pole and support therefor shown mounted in operative position.

Fig. 2 is an enlarged vertical sectional view of the sleeve, and portions of parts associated therewith.

Fig. 3 is an enlarged view, partly in side elevation, partly in elevation, and partly broken away, of portions of the pole, one beam, an inclined brace bar and a transverse brace bar, assembled in operative position.

Fig. 4 is a perspective view of one of the brace bars, broken away, and a ring which is to form the flange thereof and which is shown detached.

Fig. 5 is a plan view of what is shown in Fig. 1.

Fig. 6 is an enlarged horizontal sectional view through the pole and the inner ends of the beams, taken on the line 6—6 of Fig. 7.

Fig. 7 is a central vertical sectional view of the parts shown in Fig. 6, that is, the lower end of the pole and the inner ends of the supporting beams.

Similar reference characters designate similar parts in the different views.

1 designates a tubular center pole adapted for use in merry go rounds, carousels and the like, and which, as shown in Figs. 6 and 7 is provided adjacent to and above its lower end with a plurality of radial holes 2, in which are adapted to be removably fitted projections 3 on the inner ends of radial supporting horizontal beams 4, which may be H beams, as shown, and each of which is provided at its inner end with an upwardly extending lip 5 adapted to be extended upwardly into the lower end of the pole 1 and to engage the inner periphery thereof, whereby the beam is held from outward longitudinal movement, and by which the lower end of the pole is supported. The projections 3 hold the beams 4 and pole 1 from relative vertical movement.

In assembling the pole and beams, the lips 5 are first inserted into the lower end of the pipe, and the beams then swung upwardly at their outer ends until the projections 3 enter the holes 2. Bracing means is then employed to hold the outer ends of the beams 4 from moving downwardly.

Such bracing means comprises, preferably the following described parts.

Mounted on the pole 1, and preferably rigidly fastened thereto, is a sleeve 6, which is provided with a plurality of radially located upwardly and outwardly inclined, and preferably arcuate grooves 7, Fig. 2. The pole 1 is disposed so that the centers of the grooves 7 are respectively in the same vertical radial planes as the corresponding centers of similarly disposed arcuate grooves 8, provided one on the upper side of each beam 4 adjacent to the outer end thereof.

Bracing bars 9 are each provided at each end with an annular peripheral flange 10. The flanges 10 on the upper ends of the bars 100

9 are respectively fitted in the grooves 7 in the sleeve 6, and the flanges 10 at the lower ends of the bars 9 are respectively removably fitted in the grooves 8 in the beams 4. The bars 9 may be placed into the grooves 7 and 8 from the outer side and the grooved portions of the sleeve 6 and beams 4 will hold the bars 9 from longitudinal movement and from movement laterally in all directions excepting outwardly. The pole 1 will thus be firmly braced in the vertical position on the beams 4.

To hold the bars 9 releasably from being moved laterally outwardly, I provide transverse bracing means, which preferably connects the bars 9 with the pole 1. Such transverse bracing means may comprise the following described parts.

The pole 1 intermediate of the holes 2 and 20 the sleeve 6 has a plurality of upwardly facing arcuate grooves 12, Fig. 3, whose centers are located in the same vertical radial planes respectively as the bars 9. Each bar 9 is provided on its inner side in the horizontal plane 25 of the grooves 12 with an upwardly facing arcuate groove 11.

Transverse horizontal bracing bars 13 are provided at their ends with peripheral flanges 14, which on one set of ends of the bars 13 are respectively mounted in the grooves 12 in the pole 1. The other ends of the bars 13 have their flanges 14 respectively mounted in the grooves 11 in the bracing bars 9. The grooved portions 11 of the bars 9 35 and the grooved portions 12 of the pole 1 hold the bars 13 from endwise movement and from movement in any direction excepting upwardly. The bars 9 are thus held from outward lateral movement until the bars 13 have 40 been lifted out of the grooves 11 and 12.

The flanges 10 on the bars 9, and the flanges 14 on the bars 13 are preferably made as follows. A ring 14, Fig. 4 is fitted on the end of a tubular bar, as 9, Fig. 4, and is welded thereto by making the weld at the inner ends of radial holes 15 with which the ring is provided. In so welding at the inner ends of the holes, the welding or fused material does not deface and make irregular the outer ends 50 and outer periphery of the ring, as the welding occurs at the inner periphery of the ring spaced from the ends thereof. The flange 14 thus formed may be neatly fitted in a machined groove 7 or 8 provided therefor in the sleeve 6 and in each beam 4. The above description also applies with the same effect to the making of the flanges 14 on the bars 13. Rings provided with radial holes are fitted on the bars 13 and then welded thereto in the 55 holes of the rings.

In assembling the pole and other parts, the pole 1 may be disposed in a slightly slanting position from the horizontal, and the lips 5 of two opposite beams 4 are slipped into the lower end of the pole and the beams 4 are

swung upwardly until the projections 3 thereof enter the adjacent holes 2 in the pole.

The brace bars 9 are then mounted in the sleeve grooves 7 and the grooves 8 in the two beams 4. The transverse brace bars 13 are then fitted in the grooves 11 of the bars 9 and in the grooves 12 in the pole 1. The next beam 4 is then fastened in like manner to the upper side of the pole 1, and is held in position by the insertion of its brace bar 9, the latter being secured by its transverse brace bar 13. It will be noted that each of the grooves 7, 8 and 12 has a distance between its ends, as measured diametrically of the adjacent brace bar, not less than the diameter of the flange located therein. By means of this construction, the bars 9 and 13 may be inserted into or removed laterally, without endwise movement, from the grooves containing them, thereby making their insertion 55 or removal independent of pole 1 or beams 4, and providing a very simple and quickly assembled or disassembled structure.

The pole 1, with the inserted beams 4, are then tilted so that the pole 1 is substantially 90 upright, or enough past the vertical to enable the lip 5 of the last beam 4 to be inserted into the lower end of the pole, after which the last named beam is swung upwardly until its projection 3 enters the adjacent hole 2 in the pole 1. The brace bars 9 and 13 of the last inserted beam are then positioned in their operative positions, whereby the pole is securely anchored to the beams 4. The beams 4 and pole 1 may then be adjusted to a position in which the pole will be vertical and the beams 4 horizontal.

To disassemble the structure, the operation above described is reversed, the brace bars 13 being first removed to permit the removal 105 of the brace bars 9. By means of the interlocking means shown and described, connecting the pole 1 with the beams 4 and braces 9 and 13, the parts are enabled to be quickly assembled and held together without any accessory means, such as bolts and nuts.

I do not limit my invention to the structure shown and described, as many modifications, within the scope of the appended claims, may be made without departing from the spirit of 110 my invention.

What I claim is:

1. In a center pole and its support, a center pole having radial holes, radial beams upon which the lower end of said pole rests 120 provided respectively with projections respectively entering said holes and respectively provided with lips which extend upwardly into said pole, and bracing means connecting said beams and said pole above 125 said holes.

2. In a center pole and its support, a center pole having radial holes, radial beams upon which the lower end of said pole rests 130 provided respectively with projections respec-

tively entering said holes and respectively provided with lips which extend upwardly into said pole above said holes, a sleeve on said pole having upwardly and outwardly 5 facing grooves whose centers are respectively in the radial planes of said beams, and inclined brace bars respectively supported on said beams and at their upper ends having peripheral flanges respectively removably fitted in said grooves.

3. In a center pole and its support, a center pole having radial holes, radial beams upon which the lower end of said pole removably rests provided respectively with projections 15 respectively entering said holes and respectively provided with lips which extend upwardly into said pole, each beam on its upper side having an upwardly and outwardly facing groove, a sleeve on said pole above said 20 holes having upwardly and outwardly facing grooves having the same angular position about the longitudinal center of the pole as the grooves in said beams, and inclined brace bars, each having at its ends peripheral flanges 25 respectively removably fitted in the adjacent groove in said sleeve and in the groove of the adjacent beam.

4. In a center pole and its support, a center pole having radial holes, radial beams upon 30 which the lower end of said pole rests provided respectively with projections respectively entering said holes and said beams having respectively lips which extend upwardly into said pole, each beam having an upwardly 35 and outwardly facing groove, a sleeve on said pole above said holes having upwardly and outwardly facing grooves whose centers are respectively in the vertical radial planes of said beams, inclined brace bars having at one 40 set of ends peripheral flanges respectively removably fitted in the grooves in said sleeve, the other ends of said brace bars having respectively peripheral flanges removably fitted in the grooves in said beams, and removable 45 transverse braces respectively connecting said brace bars with said pole intermediate of said holes and said sleeve.

5. In a center pole and its support, a center pole having radial holes and above said 50 holes having upwardly facing grooves whose centers are in different vertical radial planes, radial beams upon which the lower end of said pole rests disposed respectively in said radial planes of said groove centers and provided respectively with projections respectively removably mounted in said holes and having respectively lips which extend upwardly into said pole, each beam having an upwardly and outwardly facing groove, a 55 sleeve mounted on said pole above said first named grooves and having respectively in the said radial planes of said groove centers upwardly and outwardly facing grooves, inclined brace bars having at one set of ends 60 peripheral flanges removably fitted in the

grooves in said sleeve and at the other ends having peripheral flanges removably fitted in the grooves in said beams respectively, said inclined brace bars having respectively on their inner sides upwardly facing grooves, and transverse brace bars having at their ends peripheral flanges removably mounted in the grooves respectively in said pole and in said 70 inclined braces.

6. In a center pole and its support, a center pole, radial beams upon which the lower end of said pole rests and to which the center pole is removably fastened, said beams having respectively upwardly and outwardly inclined grooves, a sleeve mounted on said pole, and provided with upwardly and outwardly inclined grooves having the same angular position about the longitudinal center of the pole as the grooves in said beams respectively, and brace bars having peripheral flanges 85 respectively removably fitted in the grooves in said sleeve and having peripheral flanges respectively removably fitted in the grooves in said beams, the distance between the ends of each of said grooves, as measured diametrically of the adjacent bar, being not less than the diameter of the flange located therein.

7. In a center pole and its support, a center pole, radial beams supporting and fastened to said pole and having respectively upwardly and outwardly inclined grooves, a sleeve mounted on said pole having upwardly and outwardly inclined grooves having the same angular position about the longitudinal center of the pole as the grooves in said sleeve, inclined brace bars having peripheral flanges respectively removably fitted in the grooves in said sleeve and having peripheral flanges respectively removably fitted in the grooves in said beams, the distance between the ends of each of said grooves, as measured diametrically of the adjacent bar, being not less than the diameter of the flange located therein, and releasable means for holding said brace bars from movement out of the grooves in which 100 they are fitted.

8. In a center pole and its support, a center pole having radially disposed upwardly facing grooves, radial beams on which said pole rests and to which it is removably fastened, said beams having the same angular position about the longitudinal center of the pole as said grooves, a sleeve mounted on said pole, inclined brace bars fastened to said sleeve removably and removably fastened to said beams and provided at their inner sides respectively with upwardly facing grooves, and transverse brace bars having peripheral flanges respectively removably fitted in the groove in said pole and having peripheral 115 flanges respectively removably fitted in said grooves in said inclined brace bars.

9. In an apparatus of the kind described, a beam having an upwardly and outwardly inclined groove, a pole supported on said 120

beam, a sleeve mounted on said pole having an upwardly and outwardly inclined groove having the same angular position about the longitudinal center of the pole as the groove in said beam, and a brace bar having peripheral flanges respectively removably fitted in said grooves, the distance between the ends of each of said grooves, as measured diametrically of the adjacent bar, being not less than the diameter of the flange located therein.

10. In an apparatus of the kind described, a beam having an upwardly and outwardly facing groove, a pole supported on said beam, and having an upwardly facing groove, a sleeve mounted on said pole and having an outwardly and upwardly facing groove having the same angular position about the longitudinal center of the pole as the groove in the beam and the groove in said pole, a brace bar having peripheral flanges respectively removably fitted in the grooves in said sleeve and in said beam and having on its inner side an upwardly facing groove, and a transverse brace bar having peripheral flanges respectively removably fitted in said groove in said pole and in said groove in the first named brace bar.

In testimony whereof I have signed my name to this specification.
